INVENTOR

MOLLIE L. GROSSMAN

BY Chas. C. Lee
ATTORNEY

UNITED STATES PATENT OFFICE.

MOLLIE L. GROSSMAN, OF NEW YORK, N. Y.

TOILET ARTICLE.

1,330,372.

Specification of Letters Patent. Patented Feb. 10, 1920.

Application filed August 29, 1918. Serial No. 251,983.

To all whom it may concern:

Be it known that I, MOLLIE L. GROSSMAN, a citizen of the United States, and a resident of New York city, in the county of 5 New York and State of New York, have invented certain new and useful Improvements in Toilet Articles, of which the following is a specification.

The invention pertains more particularly 10 to a novel handkerchief and to the combination therewith of a specially held and concealed powder-puff.

The purpose of the invention is to provide a combined handkerchief and powder-puff, with powder thereon, so constructed and arranged that the powder-puff is concealed within the handkerchief, but may nevertheless be used for the purpose of applying powder to one's face without the 15 fact being observed by others. The handkerchief is of the usual fine fabric through the interstices of which the powder may pass on the application of the handkerchief to the face, and this handkerchief has a 20 definitely located draw string defining an outline and adapted on being drawn together to form a pocket around a small powder puff placed within said outline, whereby the powder puff becomes concealed, 25 but may nevertheless without loosening the draw-string or other fastening, be employed for applying powder to one's face, the powder passing through the interstices of the 30 material of the handkerchief. By loosening the draw string the powder-puff may be 35 removed and fresh powder applied thereon and then placed back into the handkerchief or, if it should be so desired, the handkerchief may after the removal of the powder-puff, be laundered.

The invention will be fully understood from the detailed description hereinafter presented, reference being had to the accompanying drawings, in which:

45 Figure 1 is a top view of a handkerchief embodying my invention, the powder-puff being shown as placed within the outline defined by the draw-string and its pocket, this being the preliminary position given to 50 the puff prior to the same being inclosed within the handkerchief;

55 Fig. 2 is a sectional view on an enlarged scale and partly broken away, through the same, taken on the dotted line 2-2 of Fig. 1;

Fig. 3 is a top view of the handkerchief

after the ends of the draw-string have been pulled to close the handkerchief around the powder-puff, and

Fig. 4 is an enlarged sectional view 60 through a portion of the same, taken on the dotted line 4-4 of Fig. 3.

In the drawings, 10 designates the handkerchief, and 11 the powder-puff, which is a well-known commercial article and usually formed of wool and having a piece of ribbon 12 at the upper side thereof for convenience in dipping the puff into or against 65 toilet powder.

The handkerchief 10 is of the usual fine 70 texture employed in the manufacture of ladies' handkerchiefs, and upon the face of this handkerchief I sew a tape or binding 13, preferably arranged in circular outline and sewed at its opposite edges directly to 75 the handkerchief, whereby a pocket, open at both ends, is created to receive the draw string or piece of ribbon 14. The tape or binding 13 lies flat upon the surface of the handkerchief and therefore in itself does 80 not present any disagreeable projecting surfaces, and in addition does not interfere with the handkerchief being laundered according to usual methods. I preferably arrange the tape or binding 13 in the outline 85 of a circle or split ring at the center of the handkerchief, the diameter of the circle at the inner edge of the tape or binding being sufficient to permit the handkerchief to be drawn over upon the puff 11. 90

The puff 11 after having received some 95 toilet powder on its lower surface, is placed centrally within the outline of the tape or binding 13 and draw-string 14, as shown in Fig. 1, and then the two ends of the draw-string are pulled to close the material of the handkerchief about the tape or binding 13. 100 over upon the puff 11, thereby inclosing the puff in a pocket made of the material of the handkerchief itself, this being one of the important features of my invention. After the ends of the draw-string 14 have been pulled to close the material of the handkerchief about the puff 11 the ends of said string may be tied together, as shown in Fig. 3, thereby securely confining the puff 11 in correct position. Any straining caused by pulling on the draw-string 14 is taken mainly by the tape or binding 13 and thus 105 injury to the fine fabric of the handkerchief 110 is avoided.

After the puff has been secured in place

within the pocket 15 formed by the handkerchief, the handkerchief may be used for its ordinary purposes as well as for applying powder to the face, the closed end of the 5 said pocket being applied on the face and the material of the handkerchief being such that the powder may pass through the interstices thereof.

When it is desired to remove the powder-puff 11 from the handkerchief, the ends of the draw-string 14 may be untied and the outline defined by the tape or binding 13 opened outwardly from the position shown in Figs. 3 and 4 to that shown in Figs. 1 15 and 2, thereby releasing the puff and leaving the handkerchief smooth and flat.

The invention imparts to the handkerchief the very great convenience of being able to inclose a powder-puff and permit 20 the use of the same without attracting attention; and it is to be noted that the handkerchief keeps the powder-puff sanitary, as the puff never touches the face. It is well known that the perspiration and dust on a 25 person's face would soon soil a powder-puff, necessitating frequent changes, which, with the use of my invention, are avoided. I employ the expression "powder-puff" herein in a generic sense, meaning thereby any suitable 30 holder for toilet-powder which may be inclosed in the handkerchief and permit the powder to pass through the interstices of the same to the face.

What I claim as my invention and desire to secure by Letters-Patent, is:

1. As a new article of manufacture, a handkerchief of textile material of fine mesh through which toilet powder may be caused to pass, the same having a binding strip sewed thereto circumscribing a definite outline and affording a pocket for a draw-string and having also a draw-string extended through said pocket, and the material of the handkerchief within said outline being adapted to receive a powder-puff, with powder thereon and with the powder-carrying face of the puff against the body of the handkerchief, and to be folded about the same by the drawing of said string. 35 40 45

2. As a new article of manufacture, a handkerchief of textile material of fine mesh through which toilet powder may pass provided with a powder puff, a pocket for the same and means for securing said pocket in closed condition to confine the puff, said 50 55 pocket concealing both faces of the puff, whereby the powder-carrying face of the puff may be concealed against and used through the material of the handkerchief.

Signed at New York city, in the county of 60 New York and State of New York, this 27th day of August, A. D. 1918.

MOLLIE L. GROSSMAN.
